United States Patent Office

Des. 229,272

Patented Nov. 20, 1973

229,272

HAND OPERATED MEAT TENDERIZER

Fernand Michel Allinquant, 53 Avenue Le Notre, and
Jacques Gabriel Allinquant, 12 Avenue Arouet, both
of Sceaux, France

Filed July 27, 1971, Ser. No. 166,649

Term of patent 14 years

Int. Cl. D7—04

U.S. Cl. D7—101

FIG. 4FIG. 5FIG. 1 is a side elevational view of a hand operated meat tenderizer showing our new design;

FIG. 2 is a top plan view thereof;

FIG. 3 is an end elevational view thereof;

FIG. 4 is a perspective view thereof; and

FIG. 5 is a bottom plan view.

We claim:

The ornamental design for a hand operated meat tenderizer, as shown.
